UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

RIBBON-VIBRATOR.

1,222,327.

Specification of Letters Patent. Patented Apr. 10, 1917.

Application filed April 25, 1914. Serial No. 834,556.

To all whom it may concern:

Be it known that I, ALVAH C. ROEBUCK, a citizen of the United States, residing at Woodstock, in the county of McHenry and 5 State of Illinois, have invented certain new and useful Improvements in Ribbon-Vibrators, of which the following is a specification.

This invention relates to typewriters in 10 general and to ribbon vibrators in particular, and is designed to provide simple, efficient and durable improvements in mechanisms of this class.

For the attainment of these ends and the 15 accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 is a side elevation of a typewriter, partly in section, to 25 which this invention is applied; Fig. 2 is a plan view, partly in section, of a portion of the typewriter platen shift frame to which a ribbon vibrator mechanism is connected; Fig. 3 is a sectional view of the same taken 30 on the line 3—3 of Fig. 2; Fig. 4 is a detail of the mechanism taken on the line 4—4 of Fig. 2; Fig. 5 is a detail view taken on the line 5—5 of Fig. 2; Fig. 6 is a view similar to Fig. 2 of a modified form; and Fig. 7 is a 35 sectional view taken on the line 7—7 of Fig. 6.

This invention is designed primarily to 40 provide a polychrome attachment for a visible typewriter. Provision is made for utilizing the entire width of the ribbon by adjusting the vibrator to use any one of a plurality of printing zones on the ribbon. This adjustment of the ribbon vibrator makes it possible to create a plurality of 45 printing zones in each color section of a polychrome ribbon whereby the entire ribbon may be utilized.

Referring now more particularly to the 50 drawings, a typewriter frame designated generally by the reference numeral 1 is provided with key levers 2 for operating type-bars 3 to move the printing types carried thereby in contact with a ribbon 4 and making an impression thereby on a platen 5 supported by a reciprocable carriage 6. A

shift key 7 has a projection adapted to engage the platen shift frame in the well known manner. The platen shift frame comprises a shaft 8 and a shift rail 9 connected by end plates 10 and pivotally mounted on the axis of the shaft in a support 11 constituting a part of the typewriter frame. It is to be understood that the shift rail 9 moves up and down about the axis of the shaft 8, as shown in Fig. 3, to effect the shifting of the typewriter carriage frame, in the well known manner. Connecting the shaft 8 and the rail 9 intermediate the extremities thereof is a support 12 forming a bearing for a rotatable shaft 13 which has 60 an eccentric projection 14. A collar 15 holds the shaft 13 in place with respect to the support, and mounted on the shaft is a gear 16. Pivotally mounted on the shaft 13 is a frisket operating lever 17 at the lower 65 end of which a vibrator arm 18 is pivotally connected intermediate its ends. To one end of the vibrator arm a ribbon frisket 19 is connected and the other end of the arm is formed with a slot 20 in which the eccentric 70 projection 14 engages and is freely movable.

Mounted at one end in the support 12 and adjacent the other end in the end plate 10 is a control shaft 21, the outer end of which preferably extends to the side of the platen 75 shift frame and is provided with an adjusting nut 22. To the shaft is connected a gear segment 23, the teeth of which mesh with the gear 16 so that the rotation of the shaft controls the regulation of the throw of the 80 frisket.

Also secured to the shaft 21 is a toothed segment 24, the teeth of which are engaged by a spring 25 secured to the shaft 8 whereby the shaft is resiliently held in any one 85 of a number of different positions determined by the teeth of the segment. The throw of the shaft is limited by means of a cam collar 26 secured to the shaft and a projection 27 from the end piece 10 which 90 engages the cam surface to limit the throw of the shaft in both directions.

The frisket is oscillated by means of a universal bar 28 secured to a universal bar frame 28^a having a standard 29 connected 100 to the upper end of the lever 17 by means of a link 30. The movement of the type-bar 3 by the operation of a corresponding key-lever 2 causes the engagement and movement of the universal bar 28 and the 110

consequent oscillation of the universal bar. The oscillation of the universal bar frame moves the frisket by means of the lever 17 in accordance with its movement, and the regulation of the throw of the frisket is effected by means of the rotation of the shaft 21 and the geared and eccentric connection with the arm 18, as set forth.

This arrangement may be modified in a variety of ways, one of which is shown by Figs. 6 and 7, in which a support 31 is connected only to the shift rail 9 and forms a bearing for one end of a shaft 32 which extends through the end plate 10 with a nut at the outer end as before. The lever 17 is mounted directly upon the shaft 32 and the shaft is formed with an eccentric projection 33 which engages the slot 20 of the arm 18, as before explained. A toothed segment 34 having end projections 35 is secured to the shaft 32 and a spring 36 is adapted to engage the teeth of the segment 34 to permit the rotation of the shaft to a certain extent limited by the projections at the ends over which the spring cannot ride because of the engagement of the free end thereof with the plate 10 to which it is connected.

With this construction the regulation of the throw of the frisket is easily varied, the construction is simple and efficient, and the controlling shaft is carried bodily up and down with the movement of the platen shift frame. It is obvious, of course, that others may make various changes in the construction, combination and arrangement of the several parts without departing from the spirit and scope of the invention.

What I claim is:

40 1. In a ribbon vibrator, a pivoted platen shift frame, an oscillatable ribbon frisket supported thereby, an eccentric rotatable in the frame for varying the position of the frisket, a pinion connected to the eccentric, and a rotatable toothed segment meshing with the pinion to rotate it.

2. In a ribbon vibrator, a pivoted shift frame, a shaft extending parallel with the axis of the frame, a gear segment fixed on 50 the shaft, a ribbon frisket connected for operation to said segment, and a knob at the end of the shaft for rotating it.

3. In a ribbon vibrator, a shift frame comprising two bars about one of which the frame is pivoted, the other constituting a shift rail, a shaft mounted in the frame parallel with said bars, a ribbon frisket supported by the frame and oscillated with it, a gear connection between the inner end 55 of said shaft and the ribbon frisket for varying the position of the latter, and a knurled extremity at the other end of the shaft protruding from the side of the frame by means of which the position of the 60 frisket is varied.

4. In a ribbon vibrator, a shift frame having parallel bars about one of which the frame is pivoted, a ribbon frisket supported by the frame intermediate the ends thereof, eccentric means for varying the position of the frisket with respect to the frame, a pinion connected to said means, a shaft extending parallel with said bars and mounted in the frame, a toothed segment engaging the pinion, a knurled head for rotating the shaft, and means for holding the shaft in any rotated position, comprising a toothed member secured to the shaft.

5. In a ribbon vibrator, a pivoted shift frame, a ribbon frisket supported thereby, an eccentric rotatable in the frame for varying the position of the frisket, a pinion connected to the eccentric, a gear segment meshing with the pinion, a shaft to which the segment is secured, the shaft being rotatable in the frame, a stop projecting in the frame adjacent the shaft, and a collar securable to the shaft having a flattened portion engageable by the said stop to limit the rotation of the shaft in both directions.

6. In a ribbon vibrator, a shift frame comprising two parallel bars about one of which the frame is pivoted, the other constituting a shift rail, a ribbon frisket supported intermediate the ends of the frame, a shaft rotatable in the frame having one end adjacent the frisket and the other end projecting beyond one end of the frame, and means connecting the shaft and the frisket comprising a rotatable member with an eccentric projection for varying the position of the frisket when the shaft is rotated.

7. The combination with a pivoted shift frame and an oscillatable universal bar frame, of a ribbon frisket and an arm therefor supported by the shift frame, means attached both to the shift and universal bar frames for engaging the arm and oscillating the frisket, and means in connection with the shift frame for varying the position of the frisket comprising a rotatable eccentric for engaging said arm, and means operable from the side of the shift frame for rotating said eccentric.

8. The combination with a pivoted platen frame, of a ribbon frisket pivotally supported thereby, a control carried by the frame for regulating the throw of the frisket including a rotatable shaft parallel with the frame and rotatable from the side thereof, and a geared eccentric adjustment between the rotatable shaft and the frisket.

9. The combination with a pivoted platen shift frame, of a ribbon frisket pivotally supported thereby, a control carried entirely by the frame for regulating the throw of the frisket including a rotatable shaft extending to one side of the frame, an eccentric adjustment with the ribbon frisket, and a gear connection between the eccentric and a gear connection between the eccentric

adjustment and the shaft for controlling the position of the frisket.

10. In a ribbon vibrator, a pivoted platen shift frame, a ribbon frisket pivotally supported thereby, a gear segment connected to the frisket for operating it, and a rotatable shaft parallel with the axis of the frame secured to the segment and having one end extending to the side of the frame 10 for rotating the shaft.

11. A typewriter ribbon vibrator comprising a pivoted platen shift frame, a ribbon frisket, an arm pivotally connected to the frame for supporting the frisket, means 15 mounted in the frame for regulating the throw of the frisket comprising a rotatable shaft with an eccentric projection for engaging the arm, a control shaft parallel with the axis of the frame having one end 20 which extends and is rotatable from the side thereof, a geared connection between the control shaft and the other shaft for varying the position of the eccentric projection, and means for holding the control 25 shaft in any desired position.

12. In a ribbon vibrator, the combination with a lever, of a shaft on which the lever is pivoted, an oscillatable arm pivoted to the lever, an eccentric connection between 30 the arm and the shaft, means for oscillating said lever about said shaft, means for imparting motion to the shaft for adjusting said eccentric connection to change the initial position of the arm, and a pivoted platen shift 35 frame upon which all of the said parts are bodily carried and with which they are movable.

13. In a ribbon vibrator, the combination with a primary shaft, of a secondary shaft 40 parallel thereto, a rack and pinion connection between said shafts, an eccentric operated by one of the shafts, a pivoted arm engaged by the eccentric for positively moving it in either direction whereby the rotation 45 of the shafts will adjust the position of said arm, and a pivoted platen shift frame upon which all of said parts are mounted and with which they are bodily movable.

14. In a ribbon vibrator, the combination 50 with a pivoted platen shift frame, of a rotatable member carried thereby, a lever pivoted on said member, an oscillatable arm pivoted on the lever, an eccentric connection between said member and said arm, means 55 for oscillating the lever about the member, a controlling shaft also mounted in the shift frame parallel with the axis thereof with one end projecting from the side of the frame by which it is manually rotated, and 60 a rack and pinion connection between the

shaft and said member for adjusting the eccentric connection independent of the lever to which it is pivoted.

15. In a typewriter ribbon vibrator, the combination with a reciprocable universal 65 bar, of a pivoted platen shift frame, a lever pivoted in the shift frame and connected at one end of the universal bar, a ribbon vibrator arm pivotally connected to the other end of the lever, a ribbon frisket connected 70 to the arm, an adjusting shaft mounted in the shift frame parallel with the axis thereof and extending to one side of the frame, and means comprising an eccentric connection between the shaft and the arm for controlling 75 the initial position of the frisket.

16. A typewriter ribbon vibrator comprising a platen shift frame, a ribbon frisket, an arm pivotally connected to the frame for supporting the frisket, means for regulating the throw of the frisket comprising a rotatable shaft with an eccentric projection for engaging the arm, a control shaft carried by the frame, one end of which extends from the side thereof, a geared connection 80 between the shafts for controlling the regulation of the eccentric projection, resilient means for holding the control shaft in any one of a number of different positions, and means in connection with the control shaft and the frame for limiting the rotation in either direction. 85

17. In a typewriter ribbon vibrator, the combination with an oscillatable platen shift frame, an arm pivotally connected intermediate its ends with the frame having a slot adjacent one end, a ribbon frisket connected with the other end, a rotatable pin having an eccentric projection to engage in the slot of the arm for regulating the throw of the 90 frisket, a shaft carried by and movable with the frame having one end projecting from the side thereof, a gear in connection with the said pin, a segment secured to the shaft adapted to mesh with the gear, a toothed 95 member mounted on the shaft, a spring secured to the frame adapted to engage in the teeth of the said member, a collar having a cam surface secured to the shaft, and a projection on the frame adapted to engage the cam surface to limit the movement 100 of the shaft in either direction. 105

In testimony whereof I have signed my name to this specification, in the presence of two subscribing witnesses, on this 16th 110 day of April A. D. 1914.

ALVAH C. ROEBUCK.
